(57) **CLAIM**

The ornamental design for a combined LED bulbs, flexible gooseneck arms, magnifying mirror, and height adjustable floor lamp, as shown and described.

DESCRIPTION

FIG. 1 is a front view of a combined led bulbs, flexible gooseneck arms, magnifying mirror, and height adjustable floor lamp showing my new design;

FIG. 2 is a first side view of the combined led bulbs, flexible gooseneck arms, magnifying mirror, and height adjustable floor lamp;

FIG. 3 is a second side view of the combined led bulbs, flexible gooseneck arms, magnifying mirror, and height adjustable floor lamp;

FIG. 4 is a rear view of the combined led bulbs, flexible gooseneck arms, magnifying mirror, and height adjustable floor lamp;

FIG. 5 is a top view of the combined led bulbs, flexible gooseneck arms, magnifying mirror, and height adjustable floor lamp; and,

FIG. 6 is a bottom view of the combined led bulbs, flexible gooseneck arms, magnifying mirror, and height adjustable floor lamp.

The broken line portion of the figure drawing form no part of the claimed design of the combined LED bulbs, flexible gooseneck arms, magnifying mirror, and height adjustable floor lamp.

1 Claim, 6 Drawing Sheets
